UNITED STATES PATENT OFFICE

1,955,036

MATRIX-SETTING AND TYPE-LINE-CASTING MACHINE

Hermann Wilhelm Eduard Uhthoff, Berlin-Charlottenburg, Germany, assignor to the firm Typograph G. m. b. H., Berlin, Germany

Application June 26, 1933. Serial No. 677,744
In Germany July 6, 1932

11 Claims. (Cl. 199—4)

This invention relates to improvements in or modifications of the matrix-setting and type-line-casting machine according to U. S. A. application, Ser. No. 676,193 filed June 26, 1933 in which the matrix bars are circulated on wires and the set matrices are brought by means of a slider from the collecting station to the casting station, where they are line-justified and cast, and are thereupon raised to the distributing wires by a conveying device constituting the casting station. In this prior machine the adjustments still necessary in this operation are carried out positively in the correct sequence by means of only one control lever. The adjustment 5 of the lifting device, which adjustment is necessary for the selection of a predetermined character of the matrices to be cast, is in this case effected by laterally turning the control lever mounted near the key-board of the machine. 10 The said control lever, however, must be depressed again and then raised by the compositor after each setting operation for the purpose of inserting the matrix line, set in the collecting station, into the casting station and turning into position the movable line closing jaw and the starting of the machine connected therewith. In doing this, the compositor must pay attention 15 to the fact that he does not displace the control lever laterally unintentionally, for instance by depressing, through an oversight, the pawl lever locking the said control lever, and occasionally also he must also convince himself of the fact that the adjustment of the control lever corresponding to the character to be cast is still ensured, which demands increased attention and may also be prejudicial to the output of the compositor. 20

An advantage over the foregoing is secured by the present invention by the provision of a device for adjusting the cam controlling the ramp rail, the said device being independent of the control lever which is now rigidly mounted on the actuating shaft. The displacement of the cam is effected, according to the invention, by the depression of appropriate keys mounted on the key-board, the number of which keys agrees with the characters provided on a matrix bar, that is to say to the number of attainable heights 25 of lift of the ramp rail. It is here particularly advantageous that, for changing the kind of letter, the compositor has merely to depress a key, an operation with which he is conversant, and an indicating device or the depressed key 30 indicates to him at any time the kind of letter

which is actually adjusted. The position of the cam remains unaltered until another such key is depressed.

A constructional example of the invention is shown diagrammatically and by way of example 60 in the accompanying drawings, in which

Figure 1 is a part front view of the key-board and the actuating shaft of a matrix-setting machine equipped according to the invention.

Figure 2 is a plan view of Figure 1.

Figure 3 is a front view of the part carrying the actuating device for the cam, on a larger scale than Figure 1.

Figure 4 is a side view of Figure 3.

Figure 5 is a part plan of Figure 3, and

Figures 6 to 11 are front views of the individual parts shown in Figure 3 in their different positions determined by the depression of the key.

The control lever 2 to be operated by the compositor, after each setting operation, for raising the ramp rail 1, inserting the set matrices into the collecting station and turning into position the movable line clamping jaw and the starting of the machine connected therewith, is rigidly mounted on the actuating shaft 4 rotatably 75 mounted in the machine frame 3. The actuating shaft 4 is secured against lateral displacement by means of set rings 5, and carries, as in the application, Ser. No. 676,193 arms 6 and 7, which are rigidly mounted on it and are connected to 80 the rods 8, 9 operating the matrix slider or the line closing jaw and the starting clutch. The cam 11, operating the lifting rod 10 for the ramp rail 1, is mounted longitudinally slidable on the actuating shaft 4, for example by means of a slot and key, and carries, as in the application, Ser. No. 676,193 on its periphery the stepped 85 cylindrical surfaces corresponding to the different heights of lift of the ramp rail 1, which stepped cylindrical surfaces, during the depression of the control lever 2, are brought into engagement with the roller 12 provided on the lifting rod 10. The hub of the cam 11 is again constructed in the form of a sleeve provided with an annular groove 13 engaged by one arm of 90 the double-armed lever 14 mounted in the machine frame 3, which lever effects the lateral displacement of the said cam along the actuating shaft 4. The other arm of the double-armed lever 14 is hingedly engaged by a rod 15, the other 95 end of which is pivoted to an arm 16 fast on a shaft 17 rotatably mounted in the machine frame 3 below the key-board. On the shaft 17 is also secured an arm 18, by turning which the double-armed lever 14 can be moved through the me- 100

105 110

dium of the parts 17, 16, 15, that is to say, the cam 11 can be displaced along the actuating shaft 4. The free end of the arm 18 moves in front of an opening of a frame 19, formed by 5 two arcuate plates secured to the machine frame 3. On the upper end of the frame 19 is provided a stationary projection 20 against which the free end of the lever arm 18 bears in its upper position shown in Figures 1, 3, 4, 6, 7, 8 and 10. 10 A spring 21, secured for example to the machine frame 3 or to the frame 19, engages the arm 16 or the rod 15, and tends to bring the arm 18, always into the said upper position, which corresponds to the position of the cam 11 required for the normal character. The pins 22 and 23, 15 on which are secured within the frame 19 the stop levers 24 and 25, are rotatably mounted in the frame 19. The said stop levers project with their free ends into the path of the free end of the arm 18 moving in front of the frame 19. Two springs 26, 27, fixed to the plates of the frame 19, tend to hold the locking levers 24, 25, always in the position shown in Figures 3, 6, 8, 10 and 11, for locking the arm 18. A further 20 upward movement of the locking levers 24, 25, is prevented by stop pins 28, 29, fixed in the frame 19. On one end of the pin 22, which end is situated outside the frame 19, and which pin is mounted nearest the key-board and carries the upper stop lever 24, is fixed an arm 30. In the same way, the arms 31 and 32 are fixed to both ends of the pin 23, which ends are situated outside the frame 19 and which pin is remote from the key-board and carries the lower stop lever 25. The keys 33, 34, 35, provided with projections 25 and cranks, co-operate with the said arms 30, 31, 32 and with the arm 18. By means of springs 36, mounted below the key heads, the depressed keys are again returned in known manner into their initial positions.

40 The change-over device is so constructed according to the invention that, on the depression of one of the keys 33, 34, 35, the arm 18 and hence the cam 11, through the medium of the rods 17, 16, 15, 14, are brought into the position corresponding to the key depressed at the time, while simultaneously the parts controlled by the other two keys are brought out of engagement with the lever arm 18 which is, for instance held fast by them. For this purpose, there are 45 provided on the lower end of the key 33, two stop pins 37, 38 (Figures 3, 4, 6, 7) which, on the depression of this key, are brought into engagement with the arms 30 and 31 fast on the pins 22 and 23 and turn the said arms downwardly against the action of the springs 26, 27. The locking levers 24 and 25 are thereby turned 50 out of the path of the lever arm 18, so that they enter the frame 19. Thus, due to the depression of the key 33, the lever arm 18, by the action of the spring 21 always arrives in the upper position shown in Figures 3, 4, 6, 7, 8 and 10, corresponding to the position of the cam 11 necessary for the normal character, irrespective as to where it was situated before. The key 33, the 55 locking levers 24, 25 and the arms 30, 31, re-assume their initial positions under the action of the springs 36 or 26, 27, without the arm 18 and the cam 11 being moved thereby.

70 The key 34 engages by means of a pin 39 the lever arm 18, situated in its upper position (Figures 3, 6, 7, 8 and 10), and by means of a pin 40 engages the arm 32 of the pin 23, while it has no connection with the lever arms 30 and 31. Therefore on the depression of the key 34, the

lever arm 32 is turned downwardly through the medium of the pin 40, that is to say, the lower stop lever 25 connected rigidly to the said lever arm by the pin 23 is moved out of the path of the lever 18, so that the latter, if it is situated in its lower position as shown in Figure 11, is released, and is able to occupy the central position shown in Figure 9 behind the locking lever 24 held by the spring 26 in the locking position. In the same way, on the depression of the key 34, the arm 18, situated for instance in its upper position (Figures 3, 6, 7, 8 and 10), is likewise, by means of the pin 39, turned behind the stop lever 24. The key 34 is now able to re-assume its initial position under the action of the spring 36, while the lever arm 18 and hence the cam 11 are locked by the stop lever 24 and are held in the position shown in Figure 9.

The key 35 does not engage the locking levers 24, 25. On its lower end is situated a pin 41 which, in the uppermost position of the lever arm 18 (Figures 3, 6, 7, 8 and 10), bears against the said lever arm, so that, on the depression of the key 35, it is turned past the resiliently mounted stop levers 24, 25, into its lowest position shown in Figure 11, where it is held fast by the stop lever 25 situated in the locking position, even after the spring 36 has again returned the key 35 into its initial position. Only on the depression of another key for example 33 or 34 will the lever arm 18 be released again from its lowest position in the manner described in the foregoing and be brought by the spring 21 into the position corresponding to the key (33 or 34) depressed at the time. The keys 33, 34, 35 are cranked and 105 bent at their lower ends in a peculiar manner such that, on a downward movement by the same distance, they effect the corresponding movements of the lever arms 18, 30, 31 and 32.

As in the machine according to application, 115 Ser. No. 676,193, filed June 26, 1933, there is also provided according to the invention, for facilitating supervision by the compositor, a pointer 43 which moves in front of a scale 42 provided above the key-board, the said pointer being controlled 120 by the cam 11 influencing the vertical position of the ramp rail 1. This indicating device shows to the compositor at any time exactly which character has been adjusted. The pointer 43 is constituted by a double-armed lever rotatable about 125 the pin 44 fixed to the machine frame 3, and moves with its tip in front of the scale 42, on which the various kinds of letters are denoted by special marks. The other, lower arm of the pointer 43 engages the annular groove 13 of the 130 sleeve forming the bearing of the cam 11. On lateral displacement of the cam 11 on the shaft 4, the end of the pointer 43 engaging the annular groove 13 will consequently likewise be turned laterally and hence the tip of the pointer situated in front of the scale 42 will be moved correspondingly.

In the constructional example shown, the keys 33, 34, 35, after each depression, are returned again into their original positions of rest, ready 140 for operation, by means of the springs 36 arranged below their key heads. It is also possible, however, to connect the keys 33, 34, 35 in another manner already known, so that, by the depression of a key, the previously depressed key 145 is returned into its initial position, while the key last struck remains in its depressed position until it is also returned into its initial position by the striking of another key. The attention of the compositor is thereby relieved, since it is merely 150

necessary for him to cast a glance at the keys in order to ascertain which key has been depressed, that is to say, which character of the set matrices is being brought in front of the casting slot of the casting mould. Independently thereof, it is still possible for him to recognize the adjusted character by a glance at the above-mentioned indicating device 42, 43.

What I claim is:—

10 1. A matrix-setting and type-line-casting machine of the character described including in combination with a matrix collecting station, a ramp rail for effecting the vertical positioning of the matrices with respect to the collecting station, and means for operating the ramp rail including an adjustable cam and a main operating lever, of key operable means independent of the main operating lever for setting the cam.

20 2. A matrix-setting and type-line-casting machine including in combination a matrix collecting station, a casting station, a ramp rail in advance of the collecting station for effecting the vertical positioning of selected matrices, a lifting device for the ramp rail, a rotatable shaft, a cam adjustably mounted on the shaft for cooperating with the lifting device, a slider, an operable connection between the shaft and slider, an operating lever on the shaft for effecting operation of the slider and the ramp through the cam and lifting device rail, and key operable means independent of the lever for setting the cam.

30 3. A matrix-setting and type-line-casting machine as claimed in claim 1, wherein the key operable means for setting the cam includes a keyboard, keys thereon, a lever operable by depression of the keys, locking levers cooperating with the keys and last mentioned lever, and an operable connection between the last mentioned lever and the cam.

40 4. A matrix-setting and type-line-casting machine as claimed in claim 1, wherein the key operable means for setting the cam includes a keyboard, keys thereon, a lever beneath the keyboard and operable on depression of the desired key, a frame also beneath the keyboard, spring pressed lever arms pivotally mounted in the frame and positioned so as to normally be in the path of movement of the lever for engaging and releasing the lever, and an operable connection between the lever and the cam.

50 5. A matrix-setting and type-line-casting machine as claimed in claim 1, wherein the key operable means includes a keyboard, depressible keys thereon, a lever actuated by the keys, another lever for shifting the cam, a connecting rod between the levers, a spring acting in the rod for holding the latter in normal operative position, and means for limiting the swinging movement of the key operable lever.

60

65

70

75

6. Key operable means for the independent adjustment of a type setting cam in a matrix-setting and type-line-casting machine including a keyboard, keys thereon, a frame beneath the keyboard, a key actuated lever beneath the keyboard, operable connection means between the key operated lever and the cam, a spring acting to hold said connection in normal operative position, means on the frame for limiting the movement of the key operated lever, spring pressed pivotally mounted stop lever arms on the frame and in the path of movement of the key operated lever, and co-operative means on the depressible keys and on the frame for moving the stop levers at certain times out of the path of the key operated lever.

80 7. An arrangement as claimed in claim 6, wherein the co-operative means for moving the stop levers includes an arm fixed outside the frame to the pivot pin of one of the stop lever arms and two arms fixed in the same manner to the pivot pin of the other stop lever arm, and said three arms being engageable by two of the keys when depressed.

85 8. An arrangement as claimed in claim 6, characterized in that two stop pins are provided on a crank of a key and on the depression of the key turn the arms moving the locking levers and thus release the path for the free end of the lever controlling the cam.

90 9. An arrangement as claimed in claim 6, characterized in that two stop pins are provided on a key, one of which on the depression of the key turns the lever controlling the cam while the other turns the second lever arm fixed to the 100 pin so that only the lower stop lever is moved out of the path of the lever, and the latter is therefore brought by the pin or the spring behind the stop lever and is locked by the latter in its position.

105 10. An arrangement as claimed in claim 6, characterized in that a key is provided with a stop pin which bears against the said lever held in its fundamental position by the stop of the frame so that on the depression of the key, the 110 lever is brought with its free end behind the stop lever and is locked by the latter.

115 11. An arrangement as claimed in claim 6, characterized in that the keys normally returned automatically into their inoperative position by 120 springs are connected together in another manner, previously known such that, by the depression of one key the previously depressed key is automatically returned into its initial position while the key last struck remains in its depressed position until it is again brought into its initial position by the striking of one of the other keys.
